UNITED STATES PATENT OFFICE.

JAMES A. McHOLLAN, OF NEW YORK, N. Y.

LETTERING-MACHINE.

1,125,582.

Specification of Letters Patent.

Patented Jan. 19, 1915.

Application filed March 2, 1914. Serial No. 821,900.

To all whom it may concern:

Be it known that I, JAMES A. McHOLLAN, a subject of Great Britain, and a resident of the city of New York, borough of Brooklyn, county of Kings, and State of New York, have invented certain new and useful Improvements in Lettering-Machines, of which the following is a full, clear, and exact specification; such as will enable others skilled in the art to which it appertains to make and use the same.

This invention relates to typewriting machines, and more particularly to that class of such machines which permit of writing on a flat surface without the employment of cylindrical platens which ordinarily hold the material to be written upon within the body of the machine.

One of the objects of my invention is to provide a machine for typewriting lettering or descriptive matter on large maps, working drawings and the like, which, owing to the size of such drawings or maps, as well as other difficulties, cannot be lettered by the ordinary typewriting machine, and, as such work is now done by hand, by skilled draftsmen employed for that purpose, which is a slow and laborious operation, consuming much time, and involving considerable money expenditure, it will be evident that, by providing a machine which will print such work to be done accurately and expeditiously by employees more or less unskilled in drafting work, great economy will result.

Another object of my invention is to provide a machine which, when placed on the map or drawing to be lettered, may be quickly shifted from one position to another, as, for example, from a position in which the machine writes on a line parallel to one edge of the map or drawing, to a position at an inclination thereto.

The foregoing, as well as other objects, will be readily apparent from the following description, taken in connection with the accompanying drawings, in which,—

Figure 1 is a plan view of the device; Fig. 2 is a side elevation; Fig. 3 is a detail elevation; and Fig. 4 is a detail plan.

It will be understood that so far as concerns the type bar operating mechanism, the drawings are in part more or less diagrammatic, since various forms and arrangements of type bars and operating mechanism therefor may be employed, and in this application

no invention is claimed for any particular form or arrangement thereof.

Referring to the construction illustrated, A and B represent two parallel longitudinally extending rails, which at their ends are connected by two transverse rails C, D, united thereto in any desired manner, so as to form a thoroughly rigid frame or base.

The longitudinal rails A, B, are provided with angularly shaped uprights A¹, which carry one or more balls A², to act as bearings for the carriage E, mounted on the plate F, the latter having fingers F¹ projecting within the uprights A¹. The support A¹ also carries a longitudinally extending rack bar G, meshing with the teeth of which is a pinion H¹ carried by the carriage E, which pinion may be actuated in any well known manner to cause the carriage E to move longitudinally on the ball bearing supports A¹. The movable carriage E also embodies a plurality of transverse rails H, I, which are similar in form and construction to the longitudinal rails A, B.

The type carrying and type operating mechanism are movable as a whole along the rails H, I, being provided with a pinion J carried thereby and adapted to travel on the rack bar I¹; said pinion being actuated in any suitable manner. The type bars are illustrated in whole at K, the type being at the upper portion thereto as at K², and the bars being pivoted at, say, K³; the direction of movement thereof being indicated in dotted lines. The keys for operating said bars are indicated at L, the spacing keys and upper and lower case keys at M, N and O, respectively; all of this mechanism being carried by a suitable frame indicated at P. The frame P also carries a guide Q for a ribbon Q¹, the type bars making their impression through the open portion of the guide indicated at Q². It will be understood, however, that any form of ribbon guide operating by any well known form of ribbon operating mechanism may be employed, the form of ribbon guide shown being designed more particularly here for diagrammatic illustration.

Each of the end rails C, D, is provided with openings R, R¹, within each of which openings is carried a roller R² and R³; said rollers being respectively mounted on axles R⁴, R⁵, projecting within bearings in lugs R⁶ formed on the end rails C, D.

Juxtaposed to each of the rollers R^2 , R^3 is a friction member indicated at S , S^1 ; each of these friction members comprises a head portion T provided with outwardly extending pins or projections, T^1 , having movable or sliding engagement with the rail D , and a shoe portion T^2 , which is grooved to conform to a portion of the periphery of the rollers R^2 , R^3 . The shoes T^2 may be formed of any suitable material such as wood, bronze metal or the like. A spring T^3 is connected at one end to the pins or projections T^1 , and at the other end to the axles R^4 , R^5 , the function of which is to normally retain the shoes against the peripheries of the respective rollers R^2 , R^3 .

Pivotedly connected to each set of friction members, S , S^1 , is an operating member U , having a plurality of levers U^1 , U^2 ; the first mentioned lever being connected by a link V to the head T of the friction member S , and the latter lever being connected by the link V^1 to the head T of the friction member S^1 , in such manner that by pressing the said levers toward each other the shoes T^2 are withdrawn from the rollers R^2 , R^3 , against the action of the springs T^3 .

The operation will be readily apparent from the foregoing description. The device is placed upon any portion of the article to be written upon, indicated at X , which, for example, we will here assume to be a map of large size, say six feet square—the same being carried on the rollers R^2 , R^3 ; the handles U , U^1 , are then operated to release the shoes T^2 from the said rollers, and the device may then be moved to any portion of the map at which the work of lettering is to begin. The type bars are manipulated to do any portion of the work running along parallel lines, parallel, for example, to the upper edge of the map, the carriage E traveling on the longitudinal rails A , B , and the type bar mechanism being capable of movement along the transverse rails H , I . When, however, it is desired to letter or place words of description along lines at different angles to the parallel lines just referred to, the handles U , U^1 , are again pressed to release the shoes T^2 , and the machine may be quickly shifted to such new position; or from one position on the map, by the same means, the device may be readily and quickly moved from one end of the map to the other, or from the top to the bottom or to any intermediate position, without danger of crumpling or marring the surface in any manner.

I desire it to be understood that I do not

confine myself to the precise details or construction and arrangement of the invention herein set forth, as modifications may be made without departing from the spirit of the invention, as defined by the appended claims.

What I claim is:

1. The combination with typewriting mechanism for type bars adapted to write on a flat surface of a base including a plurality of parallel rails, revoluble means supporting said base and on which the same may be bodily moved to any position upon, without removing it from, said flat surface, and means adapted to lock said revoluble means against movement, to retain said base in a fixed position.

2. The combination with typewriting mechanism of a base on which said mechanism is adapted to move longitudinally, said base including a plurality of parallel rails, rollers supporting the ends of said base upon which said base may be bodily moved from and to any desired operating position, means adapted to hold said rollers, and thereby hold said base, in a fixed position, and means whereby said holding means may be released to permit movement of said rollers.

3. The combination with typewriting mechanism including type bars adapted to write upon a flat surface, of a base for said mechanism, means whereby said mechanism may be moved longitudinally and transversely of said base, rolling means supporting said base whereby the latter may be bodily moved to any position upon, without removing it from, said flat surface, and means adapted to lock said rolling means against movement, to retain said base in a fixed position.

4. The combination with typewriting mechanism including type bars adapted to write upon a flat surface, of a base for said mechanism, means whereby said mechanism may be moved longitudinally and transversely of said base, rollers supporting said base, whereby the latter may be bodily moved to any position upon, without moving it from, said flat surface, holding members adapted to contact with and normally hold said rollers in a fixed position, and manually operated means for releasing said holding members from contact with said rollers.

JAMES A. McHOLLAN.
